UNITED STATES PATENT OFFICE.

IRA M. SPONSEL, OF GOODLAND, KANSAS.

AUTOMATIC CUT-OFF DEVICE.

1,173,614.

Specification of Letters Patent. Patented Feb. 29, 1916.

Application filed August 31, 1914. Serial No. 859,539.

To all whom it may concern:

Be it known that I, IRA M. SPONSEL, citizen of the United States, residing at Goodland, in the county of Sherman and State of Kansas, have invented certain new and useful Improvements in Automatic Cut-Off Devices, of which the following is a specification.

This invention relates to an improved 10 automatic cut off device.

When filling bottles, cans, and like non-transparent containers, it is often quite difficult to determine at just what time the liquid supply thereto should be cut off. It is to 15 overcome this difficulty that the present invention is designed; said invention consisting of a float, a valve, and novel float controlled valve operating means; said means, and in fact the entire cut off device being 20 associated with the discharge spout of a vat or like receptacle to automatically cut off the liquid supply upon the delivery of a predetermined quantity to the container being filled.

25 In describing my invention in detail reference will be had to the accompanying drawings wherein like characters denote like or corresponding parts throughout the several views, and in which:

30 Figure 1 is a side elevation of a cut off device constructed in accordance with the present invention, the container to be filled being shown in section and partly broken away; and Fig. 2 is a longitudinal sectional view illustrating the position of the operating means immediately subsequent to automatic operation thereof.

Referring now to the drawings by numerals, 1 designates a vat or like receptacle 40 containing the liquid supply, the said receptacle having associated therewith and mounted thereon adjacent its bottom a suitable discharge spout 2 the bore of which is open to the receptacle interior. Said discharge spout 2 is open, as indicated in Fig. 2, to a suitable substantially frusto-conical valve casing 3, the said casing being integral with the spout and open at its diverged end to provide for movement of a substantially 45 frusto-conical valve member 4, the latter, in one position, serving as a cut off means or closure for the spout.

Pivoted as at 5 to a lug or projection 6 of the valve is an operating lever 7, said lever 55 being fulcrumed at a point intermediate its ends as at 8 in a bifurcation 9 of an arm or

standard 10 secured to or integral with the spout. The opposite end of the arm 7, when the valve is elevated or forced into a position whereby to open discharge spout 2, is 60 adapted for engagement with a suitable trigger 11 fashioned to represent a bell crank fulcrumed as at 12 in a bifurcation 13 of an arm or standard 14 also mounted on or formed integrally with said discharge 65 spout 2.

Trigger 11, as above noted, is in effect a bell crank, one end being provided with an integral lip or extension 15 adapted for overlapping engagement with the free end of 70 arm 7 to normally maintain the said arm in a substantially horizontal plane whereby to withdraw valve member 4 out of engagement with the casing 3 therefor, the said valve when thus disengaged permitting unob- 75 structed flow of the liquid contents of the receptacle 1 through the bore of discharge spout 2.

Operating in a substantially vertical plane, and extending into the bore of the 80 spout, adjacent the free end is an operating rod or staff 16, the said rod extending through an opening 17 therefor in an enlargement 18 of the spout, the engagement between the said rod and the said enlargement 85 serving as a guide means for the latter. The upper end or extremity of the said rod 16 is bent as at 18 to engage the trigger or bell crank 11, while the opposite end of the said rod has mounted thereon a suitable 90 float or buoyant member 19.

When it is desired that a suitable non-transparent container be filled with liquid drawn from the receptacle 1, the said container, (as shown to advantage in Fig. 1) 95 is positioned in such a novel and peculiar manner as to inclose the float 19. When thus positioned, valve member 4 is raised out of engagement with the casing 3 and the arm or lever 7 fastened beneath lip or extension 15 of trigger 11, the bent portion 100 18 of the operating rod 16 being also in engagement with the trigger. As the liquid contents of the container rise, the operating mechanism for the valve 4 remains inoperative and it is only upon the delivery of a predetermined quantity of liquid to the said container that the float 19 is actuated. When the said predetermined quantity has been delivered, float 19 is moved relatively 105 to the spout 2 causing trigger 11 to disengage arm or lever 7, in which event, the

weight of valve member 4 will cause the said valve to automatically seat itself in the position shown in Fig. 2 cutting off the liquid supply to the container and permitting only a predetermined quantity of liquid to be delivered thereto.

From the foregoing, taken in connection with the accompanying drawings it will be noted that the operation of the cut off device 10 is automatic, simple and positive; that said operation is controlled entirely by the rise of the liquid delivered to the container through the discharge spout with which the cut off device is associated; and that valve member 4, the same being of sufficient weight, will cause the bore of the spout 2 to be positively closed immediately subsequent to disengagement of the trigger 11 with the operating lever or arm 7.

20 In reduction to practice, I have found that the form of my invention, illustrated in the drawings and referred to in the above description, as the preferred embodiment, is the most efficient and practical; yet realizing 25 that the conditions concurrent with the adoption of my device will necessarily vary, I desire to emphasize the fact that various minor changes in details of construction, proportion and arrangement of parts may 30 be resorted to, when required, without sacrificing any of the advantages of my invention, as defined in the appended claim.

Having thus fully described my invention, what I claim as new and desire to secure by Letters Patent, is:—

35 A cut-off device for the discharge spout of a container comprising a float, a float rod to which the float is attached, an extension formed on said rod to engage with the spout and support said float, an arm integral with 40 said spout, a substantially bell crank lever carried by said arm in a plane directly above and in vertical alignment with said float rod to be engaged thereby upon movement of said float, an extension formed on one end 45 of said lever, a pivoted operating lever mounted to engage with said last mentioned extension, said operating lever and said bell crank lever being disposed exteriorly of said spout, and a weighted valve member 50 pivoted to depend from the opposite end of said operating lever from that engaging said extension, said weighted valve member being adapted to gravitate into an opening therefor in said spout to afford a cut-off for 55 the liquid discharged therethrough upon movement of the bell crank out of engagement with said operating lever.

In testimony whereof I affix my signature in presence of two witnesses.
